DOOR OPERATING MECHANISM

Clyde J. Daugherty, Cleveland, Ohio, assignor to
 The Sanymetal Products Co. Inc., Cleveland,
 Ohio, a corporation of Ohio

Application September 24, 1933, Serial No. 231,469

6 Claims. (Cl. 16—81)

This invention relates to an improved door operating mechanism adapted to be associated with a hinged door, which mechanism is substantially concealed within the rear edge of the door and adjacent door frame, which is operative to retain the door in predetermined position with a predetermined force and which is further operative upon opening and release of the door, to swing the door into predetermined position.

In accordance with this invention, a door operating mechanism is provided positioned between the hinged edge of the door and the door frame upon which the door is pivoted. A weighted member is housed and concealed within the door frame and is connected to a flexible cord of rope, wire cable, chain or other flexible material, which passes over a pulley or sheave concealed within the door frame, the pulley being free to rotate on a horizontal axis and free to swing in a horizontal plane. The cord passing over the pulley extends through a small opening in the door frame and is connected to a pivot pin embedded within the door adjacent the rear edge thereof. The pivot pin is rotatably supported by a suitable bracket contained within the door, and which is substantially concealed from view. The door operating mechanism is thus embedded and concealed in the door frame and in the door except for only a short section of cord extending between the rear edge of the door and the adjacent face of the door frame.

An object of this invention is to provide an improved door operating mechanism which may be substantially and entirely concealed from view, which is simple in construction, inexpensive to manufacture and substantially foolproof in operation.

Another object of this invention is to provide an improved door operating mechanism operating in cooperative relationship to permit pivoting of the door in either of one or both directions, and which cooperate to maintain the door in normally closed position and which will swing the door into closed position when the door has been opened.

Another object of this invention is to provide an improved door operating mechanism for building doors whose exposed parts in no way detract from but rather add to the door and door frame appearance and whose operating parts may be concealed within the door and door frame.

Various other features and advantages of the invention will be apparent from the following

particular description and from an inspection of the accompanying drawings.

Although the novel features which are believed to be characteristic of this invention will be particularly pointed out in the claims appended hereto, the invention itself, as to its objects and advantages, and the manner in which it may be carried out, may be better understood by referring to the following description taken in connection with the accompanying drawings forming a part thereof, in which

Fig. 1 is a front elevational view of a door and door frame having my improved door operating mechanism associated therewith;

Fig. 2 is an enlarged fragmentary elevational view of a door and door frame, certain parts being broken away to more clearly illustrate the door supporting hinge structure and the door operating mechanism;

Fig. 3 is an enlarged transverse cross-sectional view through the door frame looking down upon the top edge of the door and the associated hinge structure, this view being taken on line 3—3 of Fig. 2;

Fig. 4 is an enlarged fragmentary cross-sectional view through the door frame and door, showing certain details of the door operating mechanism, this view being taken on line 4—4 of Fig. 2;

Fig. 5 is an enlarged fragmentary cross-sectional view through the door frame and door hinged thereto, this view showing the door in partially open position to illustrate how the operating mechanism exerts a pull on the door intended to swing it into closed position, this view being taken on line 5—5 of Fig. 2; and

Fig. 6 is an enlarged fragmentary vertical cross-sectional view through a portion of the door frame showing certain parts of the door operating mechanism, this view being taken on line 6—6 of Fig. 2.

Similar reference characters refer to similar parts throughout the several views of the drawings and specification.

My improved door operating mechanism may be associated with any type of door or door frame, within which is provided a limited space to house and contain the operating mechanism. For purposes of illustration, I have shown in Figs. 1 and 2 a door *d* mounted within a suitable door frame including a rear frame member *f*, to which the door is hinged, a jamb member *f'* adjacent to the free edge of the door and a top frame member *f''* connecting the vertical frame members *f* and *f'*. The vertical frame

member *f* is preferably made hollow so as to house certain parts of the operating mechanism but may be made of wood, metal or other suitable material. For purpose of illustration, I have 5 shown the vertical frame member *f* in Figs. 2 to 6 inclusive, as comprising a hollow metal post, but it will be appreciated that the shape or form of the hollow frame or post member *f* to which the door is hinged is unimportant, as my 10 proved door operating mechanism may be applied to practically any hollow, vertical door frame member.

As illustrated in Figs. 1, 2 and 3, the door may 15 be formed of sheet metal, comprising spaced side wall forming panels *1* and *2* connected at the hinged edge of the door by a rear edge forming portion *3*, at the top of the door by the top edge forming portion *4* and at the bottom of the door by the bottom forming portion *5*. As illustrated more particularly in Fig. 3, the vertical 20 door frame or post member *f* may be formed as a hollow metal post generally rectangular in cross-section, defined by the door edge wall *20*, by the side face walls *21* and *22*, and a wall *23* 25 connecting the side face walls *21* and *22*. It is understood that the frame member *f* may be made in any desired shape or cross-sectional contour.

The door *d* is pivotally supported upon the 30 frame member *f* by lower pivot hinge *25* and an upper pivot hinge *26*, which may be substantially identical in construction, and only one of said hinges need therefore be particularly described. Each hinge *25* and *26* is generally angular in 35 cross-section, comprising an attaching leg portion *27* and a horizontally extending leg portion *28*, upon which the door is pivoted. The leg portions *27* and *28* may be connected by a pair of spaced web portions *29*, to stiffen and 40 strengthen the hinge structure. A pivot pin *6* is rotatably mounted upon a suitable thrust bearing provided in the horizontal leg portion *28* of the hinge bracket. The pivot pin *6* extends through the adjacent horizontal edge of the door, 45 and is provided with a threaded portion *8*, which is threaded into a threaded aperture provided in a stiffening block *7* welded to the inside face of the horizontal edge portion of the door. The pivot pin *6* is provided with a circular collared portion *9* located between the outside face of the horizontal edge portion *4* of the door and the horizontal leg portion *28* of the hinge bracket 50 *25*. The pivot pin *6* is provided with a stud portion *10* which extends through and is fixed to a rotatably mounted bearing collar *32*, which bearing collar forms a part of a bearing member seated within a recess *31* provided therefor in a generally circular boss *30* provided in the leg portion *28* of the hinge bracket. The bearing 55 member *32* is provided with a stationary exterior collar member *33*, which is fixed within the recess *31* provided in the boss portion *30*. The inner rotatable collar member *32* and the outer stationary collar member *33* are each provided with a 60 cooperating raceway which receives ball bearings *34*. Thus it will be seen that the door is pivotably mounted by a hinge structure at the top and bottom edges thereof, which is simple in design, yet unusually sturdy and strong in construction, and which permits a swinging movement of 65 the door with a minimum of frictional resistance.

The door operating mechanism comprises in its broad aspects a weight *50* connected to a flexible cord *51* trained over a pulley *52* rotatably mounted within the door frame member *f*. The oppo-

site end of the flexible cord *51* is connected to a pivot pin *18*, supported by a suitable bracket imbedded within the door adjacent the hinged edge *3* thereof. It will be noted by referring more particularly to Figs. 4 and 5, that the pin *18* to which the cord *51* is connected is positioned between the frame member *f* and the pivot pin *6* upon which the door is pivoted. Thus the weight *50* suspended within the hollow frame member *f* by the cord *51* exerts a constant pull on the cord *51* which operates to normally retain the door in the closed position illustrated in Fig. 4, and when the door is open, as illustrated in Fig. 5, the constant pull exerted by the cord *51* upon the rear edge of the door operates to pull the door into closed position when the door is released.

The pulley *52* may be conveniently mounted upon a relatively flat plate *40*, which is set within a door frame opening *39*, which opening is formed by cutting away a section of the depressed wall portion *20a* of the door frame wall *20* adjacent the hinged rear edge of the door. The opening *39* may be cut to substantially conform to the shape of the flat supporting plate *40* and the outside face of the supporting plate *40* may, if desired, be held substantially flush with the outside face of the depressed wall portion *20a* of the frame member *f*. The plate *40* may be held in a fixed position at each end thereof by a connecting plate *41*, into which is screwed a pair of screws *42* extending through the depressed wall portion *20a* of the frame member and by a pair of screws *43* extending through the adjacent end of the supporting plate *40*. The door operating mechanism including the weight *50*, pulley *52* and the mounting therefor, is thus all supported by and concealed within the frame member *f* by the supporting plate *40*. It will be understood that if desired, supporting plate *40* might also be entirely concealed within the hollow frame member *f*, but preferably it is so arranged that it can be easily inserted and removed from the door frame.

The plate member *40* is provided with a pair of spaced inwardly extending lug portions *44* and *45*, which may be cast integral therewith, and upon which the pulley *52* is supported. The pulley *52* is rotatably mounted on a suitable pin *53* supported by a rectangular shaped pulley guide *50* formed of cast or stamped metal, the guide sheave comprising vertical guide portions *54* and horizontal portions *55* which connect the vertical portions *54*. A suitable gasket *56* is positioned between the connecting portions *55* and each of the adjacent supporting lugs *44* and *45*.

A pivot pin *57* extends through the lug *44*, the gasket *56* and the connecting portion *55* of the pulley guide, the pin *57* being headed over as at *58* to retain the pivot pin *57* in position. Likewise a pivot pin *59* extends through the supporting lug *45* through the adjacent gasket *56* and through the connecting portion *55* of the pulley guide, pin *59* also being headed over as at *60* to retain the pin in position. Thus it will be seen that the pulley *52* and its associated pulley guide may be swung in a horizontal plane with the opening and closing movement of the door *d*. The pulley *52* is provided with a cord receiving groove *52a* to retain the weight carrying cord *51* in position upon the pulley. The supporting plate *40* is provided with an opening *62* which preferably is in the form of a horizontally extending slot, as shown particularly in Fig. 5, through which the cord *51* extends.

The rear edge portion 3 of the door adjacent the opening 62 is cut away as at 11, more particularly shown in Fig. 2, so as to receive a U-shaped pivot supporting bracket which extends 5 into the interior of the door. This bracket comprises a pair of spaced horizontal extending leg portions 12 and 13, and a vertical connecting portion 14, positioned within the door interior. Securing flanges 15 formed integral with and extending laterally from each of the horizontal leg portions 12 and 13, are positioned exterior of the rear edge portion 3 of the door. A securing screw 17 extends through an opening in each of the flanges 15 and is screwed into an aperture provided 10 in a reinforcing block 16, which may be welded to the adjacent inside face of the rear edge portion 3, thus rigidly supporting the pivot bracket in fixed position. The horizontal width of the leg portions 12 and 13 may be substantially 15 equal to the distance between the inside face of door panels 1 and 2, thus maintaining the panels 1 and 2 in proper spaced relationship.

It will be noted that the rear edge portion 3 of the door is spaced from the adjacent face 20 of the door frame member *f* a sufficient distance to permit a free swinging movement of the door *d*. A pivot pin 18 is pivotally connected at the ends thereof to the spaced horizontal leg portions 12 and 13 of the U-shaped door bracket. A cord 30 connecting element 19 connects the ends of the cord 51 which projects through the opening 62 to the pivot pin 18, this connecting element 19 being provided with a collar portion 19a through which the pin 18 extends. The adjacent end of 35 the cord 51 may be fixedly held to the connecting element 19 by a set screw 63, which is designed to grip the end of the cord 51 extending into an opening 64 in the connecting element 19.

The door *d* swingably mounted in the thrust bearing provided in the horizontal leg 28 of the hinge brackets 25 and 26 insure easy swinging opening and closing movement of the door *d* thereon. The door *d* may be mounted for either left or right hand swinging movement and may 40 be made to open in either one or both directions. It will be noted by referring more particularly to Figs. 4 and 5 that the pivot pin 18 to which the cord 51 is connected is positioned between the pulley 52 and the hinge pins 6, the weight 50 45 vertically movable within the frame member *f* maintaining a uniform pull on the cord 51 and a corresponding pull on the pivot pin 18 exerted in the direction of the frame member 20. When the door is closed, as shown in Fig. 4, the pivot 55 pin 18 is substantially in alignment with the hinge pin 6 and the pulley 52, thus retaining the door in closed position. When the door is swung open, as shown in Fig. 5, the pivot pin 18 is moved out of alignment with a straight line 60 drawn between the hinge pins 6 and the cord receiving groove 52a of the pulley 52 and in this position the weight 50 exerts a constant pulling force on the rear edge of the door which tends to pull the door into closed position. The size of 65 the weight 50 is such as to exert the desired closing force on the door, depending upon the weight of the door and the force required to overcome the hinge friction. The weight 50 is also so proportioned as to movably fit in the frame mem- 70 ber *f*. The rear edge 53 of the door is sufficiently cut away to permit free swinging movement of the connecting element 19 which connects the cord 51 with the pivot pin 18.

It will be appreciated that the door operating 75 mechanism may be positioned where desired

along the rear edge of the door, but for smooth operation it is preferably positioned either equidistant between the spaced hinges or nearer the lower hinge which, due to the weight of the door, supplies the greatest resistance to swinging 5 movement of the door. The door operating mechanism is entirely concealed within the door frame and within the rear edge of the door except only for a short section of cord 51 which is visible between the rear edge of the door and 10 the adjacent door frame. The door operating mechanism is simple in design, inexpensive to construct, and substantially foolproof in operation and operates with a minimum of frictional resistance. All coil springs and like devices 15 which weaken upon use, whose efficiency otherwise become impaired in use, are eliminated. The door operating mechanism as herein disclosed does not in any way mar or detract from the appearance of the door or door frame, and 20 the parts of the operating mechanism can be readily assembled as a complete unit and inserted in the door and door frame quickly and without difficulty.

While certain novel features of the invention 25 have been disclosed and are pointed out in the annexed claims, it will be understood that various omissions, substitutions and changes may be made by those skilled in the art without departing from the spirit of the invention. 30

What is claimed is:

1. In a door and door frame assembly having hinges fixedly connected to said frame and pivotally connected to the door at a point spaced from the rear edge of the door, of a door operating 35 mechanism operative to retain said door in or move said door when open into closed position, said mechanism including a weighted member contained within said door frame and movable vertically therein, lugs supported by said door 40 frame and extending inwardly thereof, a pulley guide positioned between said lugs and pivotally connected thereto for swinging movement in a generally horizontal plane, a pulley rotatably mounted upon said pulley guide for rotative 45 movement about a generally horizontal axis, a flexible cord connected to said weighted member trained over said pulley and extending outwardly through a side wall of said door frame, and means for connecting said cord to said door at 50 a point located between the pivot points of said hinges and said door frame.

2. In a door and door frame assembly having hinges fixedly connected to said frame and pivotally connected to the door at a point spaced 55 from the rear edge of the door, of a door operating mechanism operative to retain said door in or move said door when open into closed position, said mechanism including a weighted member contained within said door frame and movable vertically therein, a bracket having a normally flat face portion removably connected to the side face of said door frame adjacent to the rear edge of the door, said bracket closing an opening in said side face of the door frame, lug portions 60 associated with said bracket extending into said door frame, a pulley guide positioned between said lugs and pivotally connected thereto for swinging movement in a generally horizontal plane, a pulley rotatably mounted upon said pulley guide for rotative movement about a generally horizontal axis, a flexible cord connected to said weighted member trained over said pulley and extending outwardly through a side wall of 65 said door frame, and means for connecting said 70 cord to said door.

cord to said door at a point located between the pivot points of said hinges and said door frame.

3. In a door and door frame assembly having hinged fixedly connected to said frame and pivotally connected to the door at a point spaced from the rear edge of the door, of a door operating mechanism operative to retain said door in or move said door when open into closed position, said mechanism including a weighted member contained within said door frame and movable vertically therein, lugs supported by said door frame and extending inwardly thereof, a pulley guide positioned between said lugs and pivotally connected thereto for swinging movement in a generally horizontal plane, a pulley rotatably mounted upon said pulley guide for rotative movement about a generally horizontal axis, a flexible cord connected to said weighted member trained over said pulley and extending outwardly through the side wall of said door frame, a U-shaped bracket extending into said door through an opening provided in the rear edge thereof, and means for pivotally connecting said cord with said bracket at a point located between the pivot points of said hinges and said door frame.
4. In a door and door frame assembly having hinges pivotally connecting the door to the frame, of a door operating mechanism operative to retain said door in or move said door into a predetermined position, said mechanism including a weighted member contained within said door frame and movable vertically therein, a pulley rotatably mounted within said door frame, a pivotally mounted guide rotatably supporting said

pulley permitting angular swinging movement thereof, a cord connected to said weighted member extending over said pulley and outwardly through said door frame, and a pivot pin connected to said door at a point located between the pivot points of said hinges, said cord being connected to said pivot pin.

5. In a door and door frame assembly having hinges pivotally connecting the door to the frame, of a door operating mechanism including a weighted member contained within said door frame and movable vertically therein, a cord connected to said weighted member and extending outwardly through said door frame, means within said door frame for guiding said cord, a U-shaped bracket extending into said door through an opening provided in the rear edge thereof, and means for pivotally connecting said cord to said bracket at a point located between the pivot points of said hinges.

6. In a door and door frame assembly having hinges pivotally connecting the door to the frame, of a door operating mechanism including a weighted member contained within said door frame and movable vertically therein, a cord connected to said weighted member and extending outwardly through said door frame, means within said door frame for guiding said cord, a U-shaped bracket member extending through an opening in the rear edge of said door, a pivot pin pivotally connected to said bracket at a point located between the pivot points of the hinges, and an element connecting said cord to said pivot pin.

CLYDE J. DAUGHERTY. 35
